UNITED STATES PATENT OFFICE.

HARRY GOODWIN AND WILLIAM R. ROWE, OF NEW YORK, N. Y.

SIZE-DETERMINER.

No. 896,205.

Specification of Letters Patent.

Patented Aug. 18, 1908.

Application filed October 8, 1907. Serial No. 396,366.

To all whom it may concern:

Be it known that we, HARRY GOODWIN, residing at New York city, borough of the Bronx, in the county of New York and State 5 of New York, and WILLIAM R. ROWE, residing at New York city, borough of Brooklyn, in the county of Kings and State of New York, citizens of the United States, have invented certain new and useful Improvements 10 in Size-Determiners, of which the following is a specification, reference being had to the accompanying drawings, forming a part thereof.

Our invention relates to improvements in 15 devices for determining the dimensions of figures, as drawings, cuts, proof copies and the like, when drawn to a different scale; and, particularly, for determining the length of one side of such a figure upon a different (reduced or enlarged) scale, the length of the other side upon that scale being given, whereby both sides of the figure upon the new scale become known and the figure may be readily constructed upon such sides as axes.

25 An object of our invention is to provide a device of this character which will prove perfectly accurate in use; susceptible of ready manipulation by unskilled persons and cheap in manufacture.

30 Another object of our invention is to provide a device of this character by means of which all mathematical computations will be rendered unnecessary and the determination made wholly by mechanical means.

35 A further object of our invention is to provide a device of this character which will not mar the surface of the paper upon which the original figure is laid out.

In the drawings illustrating the principle 40 of our invention and the best mode now known to us of applying that principle, Figure 1 is a perspective view of our new size determiner; Fig. 2 is a bottom plan view of one of the scale-bars, which is called by us the 45 base-bar of the device; Fig. 3 is a section on the line 3—3 of Fig. 1; Fig. 4 shows the device in side view, when folded and not in use; Fig. 5 shows a modified form of our new size determiner hereinafter more fully described; 50 Figs. 6, 7, 8 and 9 illustrate modified forms in which the reading-bar is pivotally mounted at the end of a swinging arm; and Fig. 10 is a sectional detail on the line 10—10 of Fig. 5.

The device consists essentially of the two 55 scale-bars *a*, *b* and the reading-bar *c*. The scale-bar *a* is called by us the base-bar of the

device and it is formed with a central longitudinal slot *d*. The other scale-bar *b* is called by us the rule and is formed at one end with a downwardly-turned flange *e* adapted to slide along the fiducial edge *f* of the base-bar *a*, whereby the two scale-bars *a*, *b* are maintained at right angles to each other. The lower face of the base-bar *a* is formed with a groove *g* which extends along the slot *d* (Fig. 60 2). Through the latter projects the free end of a screw-stud *h* the other end of which is mounted in one end of the rule *b*. A thumb-nut *i* lies in the groove *g* and engages the end of the stud *h* which projects thereinto; thus, 65 the top of the thumb-nut *i* lies flush or level with the lower face of the base-bar and permits the base-bar to lie flat upon the surface of the paper upon which it rests.

The index-bar or reading-bar *c* is adjustably fastened to the base-bar *a* by means of a screw-stud *h'* and a thumb-nut *i'*, the latter lying in the groove *g* in a manner entirely similar to the thumb-nut *i*. The reading-bar *c* is preferably made of thin, flexible material, so that it may be bent under the rule 70 *b* as shown in Fig. 1.

The reading edges *k* of the scale-bars *a*, *b* are provided with scales which may be graduated in any suitable manner. In Fig. 1 the 75 unit used is the agate measure of printers. At the zero of the scale on the base-bar is placed the point of an index-pin or guide-pin *m*; and the zero of the scale on the rule lies in the same vertical plane as the reading edge 80 *k* of the base-bar *a*.

To use the device, the base-bar *a* is placed upon the paper upon which is drawn the figure to be reproduced to a different scale; and the reading edge *k* of the base-bar is made 85 coincident with the side of the figure the length of which in terms of the new scale is known. The point of the guide-pin *m* is placed at one end of this side. The rule *b* is moved along the base-bar until its reading 90 edge *k* coincides with the division on the base-bar which indicates the length of the side in terms of the new scale to which the figure is to be drawn. The reading edge *k'* of the reading-bar *c* is then caused to pass 95 through the lower right-hand corner of the drawing *n* and at the same time to contact with the point of the guide-pin *m*. That division of the scale upon the rule *b* in which the reading edge *k'* of the bar *c* cuts the reading edge *k* of the rule *b*, will indicate the 100 length of the other side of the drawing to the 105 110

new scale upon which it is to be reproduced. It is obvious that the reading edge k' of the bar c may be first made to coincide with the diagonal of the drawing n ; and then the rule b may be brought to the division of the scale upon the base-bar a at which is set off the length of the known side of the drawing n in terms of the scale upon which it is to be redrawn. The sequence of these operations depends upon only the convenience of the operator and his individual desire in the matter and does not affect the accuracy of the final result.

In Fig. 4 the device is shown folded, as when not in use. The flange e of the rule is brought to one end of the base-bar a and the rule b is brought over the base-bar a . The index-bar c is then swung over the rule b .

In the modified form of our new device illustrated in Fig. 5, the rule o is not connected with the base-bar p but is pivotally fastened to the diagonal bar q at r . The diagonal bar q is formed with a central longitudinal slot s to permit the rule to travel along the base-bar p and the diagonal bar q . The latter is mounted free to swing about the pivot-pin t which projects through the slot u in the upper end of the base-bar and upon the upper end of which is mounted a nut v . The rule o is formed with a groove w (Fig. 10) in which is mounted free to slide the scale-plate x . To use this modified form of our device, the point of the guide-pin m is brought, as before, coincident with the upper left-hand corner of the drawing n and the reading edge k of the base-bar p is made to lie along the left side of the drawing, it being assumed that the length to which this side is to be reduced (or enlarged) is known. The reading edge k' of the diagonal bar q is made to coincide with the diagonal of the drawing n and to pass in contact with the point of the guide-pin m . The rule o is then moved along the base-bar p and the diagonal bar q , until it reaches that division of the scale on the base-bar p which indicates the length of the known side of the drawing as it will be, when reproduced. The scale-plate x is provided with a depression y at one end in which the operator may engage his thumb or forefinger and push the scale-plate x , until its zero coincides with the reading edge k' of the diagonal bar. The point where the reading edge of the base-bar p cuts the scale upon the scale-plate x indicates the length of the other side of the drawing as it will be, when redrawn to the new scale. In manipulating the rule o , it is obvious that care must be ex-

ercised to keep the reading edges of the rule and the base-bar p at right angles to each other; and in doing this the lines indicating the divisions of the scale upon the base-bar will aid materially.

In Figs. 6 and 7 the diagonal bar 2 is shown pivotally mounted upon the free end 65 of an arm 3 which is free to swing about a pivot 4 upon the upper end of the base-bar 5 . In this case the latter is not slotted.

In Figs. 8 and 9 the reading-bar k'' is shown mounted pivotally upon the free end 70 of an arm 3 in a manner entirely similar to that illustrated in Figs. 6 and 7 just referred to.

The scales shown upon the base-bar p and the rule o in Fig. 5 are inch scales; but any other suitable scales may be used. 75

We claim:

1. The combination with a pair of graduated bars movable relatively to each other and a guide-pin mounted on one of said bars and free from connection with the other of said bars; of a third bar pivotally connected with one of said graduated bars; said guide-pin being mounted below the point of pivotal connection of said third bar and the latter being adapted to lie against said guide-pin. 85

2. The combination with a pair of graduated bars movable relatively to each other and a guide-pin mounted on one of said bars and free from connection with the other of said bars, of a third bar pivotally connected 90 with the last-named graduated bar; said guide-pin being mounted below the point of pivotal connection of said third bar and the latter being adapted to lie against said guide-pin.

3. The combination with a pair of graduated bars movable relatively to each other and a guide-pin mounted on one of said bars and free from connection with the other of said bars at the beginning of the graduations 100 thereon, of a third bar pivotally connected with the last-named graduated bar; said guide-pin being mounted below the point of pivotal connection of said third bar and the latter being adapted to lie against said guide-pin. 105

In witness whereof we have hereunto set our hands at said New York city in the presence of the two undersigned witnesses this seventh day of October, 1907.

HARRY GOODWIN.
WILLIAM R. ROWE.
